UNITED STATES PATENT OFFICE.

KARSTEN KNUDSEN, OF GRAND RAPIDS, MICHIGAN, ASSIGNOR, BY DIRECT AND MESNE ASSIGNMENTS, TO ELECTRIC WHEEL CO., (ASSOCIATES,) OF SPRINGFIELD, MASSACHUSETTS.

WHEEL.

1,075,655.

Specification of Letters Patent.

Patented Oct. 14, 1913.

Original application filed May 24, 1912, Serial No. 699,583. Divided and this application filed January 6, 1913. Serial No. 740,337.

To all whom it may concern:

Be it known that I, KARSTEN KNUDSEN, a citizen of the United States of America, residing at Grand Rapids, in the county of Kent and State of Michigan, have invented certain new and useful Improvements in Wheels, (the same being a divisional part of my application for United States Letters Patent filed May 24, 1912, Serial No. 699,583,) of which the following is a specification.

My invention relates to the casings or housings and associated parts of electrically-driven wheels for trucks and other vehicles, and of other forms of wheels for other purposes, and consists of a certain peculiar wheel structure, having an easily removable front and possessing other advantageous features, all as hereinafter set forth.

The object of my invention is to produce a strong and durable wheel so constructed that the entire interior thereof becomes accessible upon the removal of the front cover plate without disturbing any of the mechanism that may be contained within the wheel.

Although the interior mechanism above referred to usually is so intimately associated with the inclosing, supporting and carrying parts therefor as to bring the combination of the whole under the general term "wheel," such term as used herein is to be understood as relating to and designating the inclosing structure and kindred members, rather than the entire combination just mentioned.

A further object is to provide a wheel of the class designated with simple but secure and easily manipulated attaching means for the aforesaid cover plate.

Other objects will appear in the course of the following description.

A preferred form of embodiment of the invention, whereby I attain the objects and secure the advantages of the same, is illustrated in the accompanying drawings, and I will proceed to describe the invention with reference to said drawings, although it is to be understood that the form, construction, arrangement, etc., of the parts in various aspects are not material and may be modified without departing from the spirit of said invention.

In the drawings, in which like numerals designate like parts throughout the several views, Figure 1 is a front elevation of one-half of a wheel which embodies my invention as aforesaid; Fig. 2, a central horizontal section through said wheel, or a section showing the parts as they would appear if looking down on so much of the structure as is shown in the first view; Fig. 3, an enlarged detail in section of a part of the wheel, which illustrates more clearly and distinctly the application of the lock-ring than does the preceding view, and, Fig. 4, a fragment of the wheel showing a slightly modified form of fastening means for the cover plate.

As illustrated in connection herewith my wheel and its appurtenances are described in detail as follows: Said wheel comprises a rim 1, front and rear plates 2 and 3, respectively, the former being styled the cover plate, and said plates having open centers to the edges of which are rigidly attached front and back hubs 4 and 5, respectively, a front lock-ring 6, and a series of bolts 7, nuts 8, and clamps 9, or in place of said clamps a single clamp in the form of a ring 10. The clamps 9 appear in Figs. 1, 2 and 3, and a portion of the ring clamp 10 in Fig. 4. The peripheral edge portion of the plate 2 is reinforced by means of an inside ring 11 which may be riveted or otherwise permanently and rigidly secured thereto, and the corresponding portion of the plate 3 is reinforced by means of inside and outside rings 12 and 13, respectively, which may be riveted or otherwise permanently and rigidly secured thereto. The bolts 7 pass through the ring 13, the plate 3, the rings 12 and 11, and the plate 2, and receive on their front terminals the clamps 9 (or the ring clamp 10) and the nuts 8.

The lock-ring 6 is wedge-shaped in cross-section and fits into a space left between the outer edges of the plate 2 and its ring 11 and the adjacent portion of the rim 1, such space being best shown at 14, in Fig. 3. When forced into the space 14 the lock-ring not only becomes wedged therein, but in turn wedges the plate 2 in place.

The clamps 9 are especially adapted both to force the lock-ring 6 to its seat and thus

to assist in securing the cover plate 2, and to serve in the capacity of direct fastening agents, when the nuts 8 are tightened on the bolts 7 against said clamps, because each clamp has a rearwardly-projecting part 15 at one end which bears on said plate while said clamp bears at the other end on the exposed wide edge of the lock-ring.

10 In cross-section the ring-clamp 10 is constructed similarly to the clamps 9 in longitudinal section, so that if such clamp 10 were cut transversely into sections each of such sections would form one of said 15 clamps 9, and said clamp 10 functions in practically the same way as do said clamps 9.

When an annular rack, as 16, is used in the wheel, as is the case in the present instance, the same is secured against the inside of the ring 12, and the bolts 7 pass through said rack.

20 The rim 1 has an internal flange 17 and by means of the bolts, nuts and other fastening members the plates 2 and 3 and attached members are clamped to said flange, the inside face of the outer edge portion of the rack 16 and the inside face of the outer edge portion of the ring 11 coming in direct contact with the back and front edges, 30 respectively, of said flange.

To gain access to the interior of this wheel, it is simply necessary to remove the nuts 8 and the clamps 9 (or clamp 10), 35 withdraw the lock-ring 6, and slip the plate 2 with its reinforcing ring 11 off of the bolts 7, all of which can be done readily and without disturbing any of the internal mechanism. The same parts and members can 40 be returned to place as readily as they were disconnected and taken off or removed.

It is understood, of course, that the hubs 4 and 5 are for the axle members upon which in practice such hubs are mounted to revolve.

What I claim as my invention, and desire to secure by Letters Patent, is—

1. The combination, in a motor wheel, with a wheel rim, a cover plate, and bolts and nuts securing said plate to said rim, of a lock-ring adapted to fit into a space between the peripheral edge of said plate and adjacent portions of said rim, and clamping means on said bolts between said plate and nuts and arranged to bear on said plate and on the exposed edge of said ring.

2. The combination, in a motor wheel, with a wheel rim, a cover plate, bolts and nuts for securing said plate to said rim, a lock-ring wedge-shaped in cross-section and adapted to fit into a space between the outer edge of said plate and adjacent portions of said rim, and a plurality of clamps on said bolts between said plate and nuts, each of said clamps bearing at its outer terminal on the exposed wide edge of said ring and having at its opposite terminal a flanged part to bear on said plate.

3. The combination, in a motor wheel, with a rim having an interior projection, and front and back plates, said plates being adapted to embrace said rim projection, of bolts passing through said plates inside of said projection, wedging means for one of said plates, and clamping and fastening means for said bolts and wedging means.

4. The combination, in a motor wheel, with a rim having an interior projection, front and back plates, and an annular rack, said plates with said rack being adapted to embrace said rim projection, of bolts passing through said plates and rack inside of said projection, wedging means for one of said plates, and clamping and fastening means for said bolts and wedging means.

KARSTEN KNUDSEN.
